DESIGN FOR A DRESS

Josephine Frazita, New York, N. Y.

Application August 30, 1943, Serial No. 111,026

Term of patent 3½ years

To all whom it may concern:

Be it known that I, Josephine Frazita, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof, on a reduced scale.

Fig. 3 is an enlarged fragmentary view of the dress shown in Fig. 1, illustrating the puffed embroidered skirt trim in detail.

The characteristic feature of my design resides in the combination on the dress disclosed of the specific skirt portion having graduated rows of intertwined puffed embroidery arranged as shown.

I claim:

The ornamental design for a dress, substantially as shown and described.

JOSEPHINE FRAZITA.
